CLAIM

(21) Appl. No.: 29/183,412

The ornamental design for a combination wall cabinet and shelf, as shown and described.

(22) Filed: Jun. 11, 2003

DESCRIPTION

(51) LOC (7) Cl. 06-04

FIG. 1 is a perspective view of a combination wall cabinet and shelf showing my new design;

(52) U.S. Cl. D6/397; D6/561; D6/480

FIG. 2 is a front elevational view thereof;

(58) Field of Search D6/432-448, 470, D6/559, 561, 567; 312/237, 278, 279, 204, 205, 224

FIG. 3 is a left side view thereof, the opposite side being a mirror image of the side shown;

FIG. 4 is a top plan view thereof; and,

FIG. 5 is a bottom plan view thereof.

The broken lines shown in FIG. 1 are for illustrative purposes only and form no part of the claimed design.
